METHOD OF AND APPARATUS FOR FEEDING
BAGS FROM A STACKWilliam E. Higginbottom, Radnor, Pa., assignor
to Benjamin C. Betner Company, Devon, Pa., a
corporation of Delaware

Application May 28, 1938, Serial No. 210,621

31 Claims. (CL. 93—8)

My invention relates to methods of and apparatus for feeding bags of paper or equivalent material, and particularly to systems for feeding bags, as from a stack thereof, individually and in succession to an assembly station at which closure elements are applied thereto to constitute assemblies later to be filled and finally closed.

In accordance with my invention, a strip of paper, or equivalent material, is fed along a path to and beyond several successive stations at which are successively performed various folding and cutting operations with eventual successive severances from the strip at intervals to form closure members for bags which are fed in succession, as from a stack, during progress of the strip, and which, in turn, are attached at an assembly station to the successively formed closure members preferably before their severance from the strip.

More specifically, the bags are removed in succession from the bottom of the stack and fed to the assembly station in position there to overlie a closure member still unsevered from the strip, and at the assembly station the bags in succession are adhesively attached to the strip; preferably, for each feeding or advance movement of the strip, a bag is removed from the bottom of the stack, the bag previously removed from the stack is fed to the assembly station, and a bag there attached to the strip is moved therewith as aforesaid from the assembly station.

My invention also resides in mechanism for removing bags individually from an end, specifically the bottom, of a stack, for feeding them to an assembly station, and for registering them at the assembly station.

My invention further resides in the methods and apparatus having the features of novelty hereinafter described and claimed.

For an understanding of my method and for illustration of a preferred apparatus for performing it, reference is to be had to the accompanying drawings, in which:

Fig. 1, in perspective, illustrates the progressive formation of closure elements from a strip of material, their attachment to bags fed from a stack, and severance of the strip between attached bags;

Fig. 1a is a detail view showing a closure element in end elevation;

Fig. 2 is a front elevation of a machine for performing the method illustrated in Fig. 1;

Fig. 3 is a plan view of the mechanism of Fig. 2;

Fig. 4 is a plan view on enlarged scale of a

bag-removing and feeding mechanism shown in Figs. 1 and 2;

Fig. 5 is an end elevational view of the mechanism shown in Fig. 4;

Fig. 6 is an elevational view of the mechanism of Fig. 5 viewed from its opposite side;

Fig. 7 is an elevational view, taken on line 7—7 of Fig. 4;

Figs. 8 and 9 are sectional views illustrative of successive steps of operation of the bag-removing and feeding mechanism;

Fig. 10, in perspective, illustrates a bag and a closure element before their assembly or attachment;

Fig. 11 is a perspective view of the completed bag and closure assembly;

Fig. 12 is a detail view showing stop mechanism;

Fig. 13 is a detail view, in top plan, of the upper blade of the bag-removing mechanism shown in Figs. 7, 8 and 9;

Fig. 14 is a detail view, top plan, of the lower blade of the bag-removing mechanism;

Fig. 15 is a detail view on enlarged scale, and in section, illustrating the construction of the stack support;

Fig. 16, in perspective, illustrates bag-registering mechanism;

Fig. 18, in perspective, illustrates schematically the elements of a stack-feeding arrangement;

Fig. 19 is an elevational view, with parts omitted and parts in section, of an alternative hopper construction;

Fig. 20 is a plan view of parts shown in Fig. 19;

Fig. 21 is a perspective of parts shown in Figs. 19 and 20; for clarity parts are omitted and other parts broken away;

Fig. 22 is a side elevational view of a modified form of bag-feeding mechanism;

Fig. 23 is a plan view of the mechanism of Fig. 22 with parts omitted and parts broken away;

Fig. 24 is a side elevational view taken in the direction of the arrows 24, 24 of Fig. 23;

Fig. 25 is an elevational view with parts omitted and parts in section of the mechanism of Fig. 23.

Referring to Fig. 1 the strip S of suitable closure material, preferably or usually paper, is fed from the roll R thereof as by the feed rolls 1, 2, through the station G at which adhesive is applied to one surface thereof as by the roll 3. As the strip S is fed beyond station G toward the assembly station A, it is met by a thin, ductile

strip of metal T which may be suitably directed by a guide 4. As the strips S and T move through station F toward the assembly station, one edge of the strip S is turned, as by the curling or folding tools 5, 6, 7, 8 and 9, to embrace the metal strip T, as shown in Fig. 1a. The composite strip ST as it emerges from the station F, consists of the flap portion BF for attachment to bags, and a rolled portion C stiffened by the enclosed strip T. As the strip passes through the station N, the flap portion BF thereof, at regular distances corresponding approximately to the width of the bags to which the closure elements are to be applied, is notched or cut, as by knives 10, 11. The notching station may be located anywhere along the path of the strip S from the time it leaves the roll R until it is severed as hereinafter explained. At the assembly station A, the upper end of one side of a bag B is pressed against an adhesive-coated flap BF of the composite strip between two successive notches.

As the feed of the strip continues, a bag is carried therewith beyond the assembly station, and a knife 12 severs the composite strip substantially in the middle of one of the notches to provide the bag and closure assembly shown in Fig. 11.

Preferably the strip S is fed intermittently or step-by-step, and during each forward movement of the strip, by amount equal to the length of one of the completed closure elements CT, and during each forward movement of the strip, a bag is removed from the bottom of the stack H thereof, as by the gripper mechanism 13, and fed to the transfer station E; concurrently a bag is fed from the transfer station E toward the assembly station A, from which there is being moved, as previously described, a bag already attached to the composite closure strip. The completed assemblies may be removed in any suitable manner, as by the conveyor belts 15 extending to any suitable destination.

This same method is suitable for formation and attachment to bags of closure elements of the type disclosed and claimed in copending application Serial No. 74,670, filed April 16, 1936, by myself and S. Norman Williams.

For illustration of a preferred mechanism for performing the various steps of the method hereinbefore briefly described, reference is made to Figs. 2 and 3 in which the motor 16, through a suitable one-time clutch, not shown, drives the main shaft 17 through pulley 18, belt 19 and pulley 20. The feed rolls 1, 2 are intermittently oscillated by rack 21. One end of the rack is pivotally connected to the block 22 adjustably secured to the crank-arm 23 on shaft 24 which is driven from the main shaft 17 of the machine through the train of gears 25, 26, 27, 28, 29, 30. For each rotation of shaft 24 the rack 21 moves forward and back; during its forward movement the pawl 25 on gear 26, which is in mesh with the rack, is, by its engagement with the ratchet-wheel 27, effective to rotate the feed roll 2 in clockwise direction to predetermined extent. The gear 28 on the shaft of the upper feed roll 1 is in mesh with a similar gear on the shaft of the lower feed roll 2 and is, therefore, concurrently rotated in opposite or counterclockwise direction. Thus the two feed rolls engage the opposite faces of the strip S to advance it to the right, as viewed in Figs. 2 and 3. While the rack 21 moves in reverse direction, or to the left, for continued rotation of shaft 24, the pawl 25 clicks idly over the ratchet 27. The extent to which the strip

S is fed for each cycle of the machine, or rotation of shaft 24, may be adjusted to suit the particular bags by proper setting of the block 22 in the slotted arm 23.

Preferably, in addition to the feed rolls 1 and 2, there are also provided the second pair of feed rolls 31, 32, and a third pair of feed rolls 33, 34. The second and third sets of feed rolls are also driven from the rack 21; specifically, upon the shaft of the upper feed roll 1 is secured gear 35 in mesh with gear 36 on shaft 37 extending lengthwise of the machine and having thereon gears 38, 39 for driving the gears 40, 41 on the shafts, respectively, of the feed rolls 31 and 33 which are suitably connected as by gears 42, 43 to similar gears on the shafts of feed rolls 32, 34.

After the machine has been set up and in condition for normal operation, the intermittent movement of the feed rolls advances the strip S step-by-step from the roll R toward the assembly station between the second and third sets of feed rolls; the strip, in its movement from the roll R toward the first folding tool 5, is pressed against the periphery of the adhesive-applying roll 3 by the sets of idler rolls 44, 45. As the roll 3 rotates, either because of its engagement with the strip S, or by a separate source of power, its periphery dips below the surface of adhesive in the pan 46, thus continuously to present fresh adhesive to the strip S as it is fed thereover.

The tools 5 to 9 are suitably shaped and disposed to engage the under, uncoated side of the strip S and cause one edge thereof to curl over during movement of the strip toward the right, thus to encircle or embrace the metal strip T. Beyond the feed rolls 1 and 2, the composite strip passes through the housing 47 in which is disposed a stationary knife 11 and a movable knife 10 cooperating therewith to notch the uncurled or flap portion T of the strip. The movable knife 10 is carried by a vertically reciprocating frame member 48, Fig. 16, carried by blocks 49 each having an opening to receive an eccentric 50 attached to the shafts 51, 51 of the machine. During rotation of the shaft, the blocks 49, 49 are lifted, raising the member 48 and so effect notching of the strip by the knives 10, 11. The parts are so timed the strip S is at rest when engaged by the notching knives 10, 11.

Preferably, and as indicated, the frame member 48 carrying the movable blade 10 is not rigidly attached to a frame member 49. A plurality of springs 52 between the upper surface of the member 49 and the lower surface of frame member 48 biases the latter upwardly, but the separation between members 48 and 49 is limited by the stop members 53.

By subsequent movements of the strip, it is finally brought to the assembly station A in front of the stack H of bags. The bags, by mechanism now described, are removed in succession from the stack and brought, in turn, into engagement with the successive closure elements formed by notching of the strip.

The stack of collapsed bags is supported in the hopper 54 comprising two plates 55, 55 supported by the frame members 56, 57; preferably at least one of the hopper members 55 is adjustable to accommodate bags of different widths. The bottom of the stack is supported by the inwardly directed flanges 58 of side member 55 of the hopper which flanges, as appear from Fig. 7, terminate short of the front edge of the stack

which is supported at its lower corner by the cross-bar 59 or equivalent. The distance between bar 59 and the forward end of the bottoms 58 is sufficiently great to permit the bottom of a collapsed bag B to swing into the gap between these members, generally as shown in Fig. 15.

Preferably, as shown in that figure, the forward end of each of the bottom members 58 is provided with a bead or abutment R extending above its upper surface so that when a stack of bags is in place, the bottom bag is slightly bowed upwardly. By so shaping the members 58, each bag, as it arrives at the bottom of the stack, is slightly flexed so that the bag bottom tends to pivot about the bead and swing into the gap between the bar 59 and the supporting plate 58 and open the fold between the bag bottom and the lower side of the bag.

Instead of providing the bottom plates 58 with a bead R there may be utilized the alternative arrangement shown in Figs. 19-21 which is better suited for a wide variety of bag sizes and bag materials. Upon the forward ends of the bottom members 58A, similar to aforesaid members 58, is pivotally mounted the tongue 151 whose extension 152 is engaged by the lower end of the screw 153, or equivalent adjustable member, supported by the crosspiece 155 which may be attached, as by welding, to one of the plates 58A. The screw 153 is accessible to the operator for adjustment during the operation of the machine to determine, for the particular bags in the hopper, that angle between the plates 58A and the tilted forward end of member 151 which is best suited to open the fold F of the bottom bag of the stack to receive the blade 85 of the transfer mechanism.

The forward end of member 151 should, as indicated in Fig. 19, engage the under face of the bag adjacent the bottom panel; therefore, if the machine is to be used for different sizes of bags, provision should be made for changing the distance between the bar 59 and the forward end of the hinged member 151. In the particular arrangement disclosed, the plates 58A are held to the bottom of the hopper sides 55 by screws which pass through openings 154, 154, Fig. 21, which are elongated to permit adjustment of the plates 58A lengthwise of the hopper.

For different sizes of bags, it is also necessary to adjust the position of the rear guide members 159; in the preferred arrangement shown in Figs. 21 and 25, the guide members 159 are provided with apertured angle pieces 162, and the hopper sides 55 are provided with slots 160 to receive bolts 161 which pass through the slots 160 and the angle members 162 to hold the guide members in their adjusted positions.

The carriage 60, Fig. 7, which reciprocates below the bottom of the stack H, comprises a cross-bar 61, one end of which extends through a slot in the frame member 57, Figs. 4 and 7, and two reciprocating members 63, 63, which at their forward ends receive the cross-bar 61 and which are provided with rack portions in mesh with the gears 64, 64 on shaft 65 extending between the frame members 56, 57, Fig. 4.

The upper edges of the reciprocating members 63, 63 are received by the flanged guide rolls 66, 66. Shaft 61 is provided with ball bearings 70 which ride between guides 149, 150. The gear 67 is secured to shaft 65 beyond the side frame 56, Figs. 4 and 5, in mesh with the rack member 68 having at one end a cam follower 69 for engaging the cam 70 on shaft 71 which extends be-

tween the frame members 56, 57. The shaft 71 is rotated in timed relation to the strip-feeding mechanism by gear 72 thereon which is driven by gear 73 on shaft 74, the speed ratios of the train of gearing being such that the cam 70 makes one revolution for each revolution of shaft 24 of the strip-feeding mechanism.

The rack member 68 is guided during its reciprocation by the idler rolls 75 and is urged toward engagement with the cam 70 by the return spring 76. For each revolution of cam 70 the shaft 65 is rotated first in one direction, and then in the other, to impart reciprocation to the carriage 60 below the stack of bags.

The cross-bar or rod 61, which, as previously stated, extends through a slot 62 in the frame member 57, is provided beyond the frame member with a crank arm 77, Figs. 4 and 6, from which extends pin 78 received by the elongated slot 79 in one arm 80 of the bell-crank lever whose other arm 81 carries a cam follower roll 82 which engages a periphery of a cam 83 on shaft 71. Consequently, for each rotation of the shaft 71 the bell-crank lever is rocked to turn the cross-bar 61 of the reciprocating carriage 60 through a substantial angle. As appears from Figs. 8 and 9, during movement of the cross-bar 61 toward the left, the blade 84 carried by the bar enters the fold F between the bag bottom and the side against which it previously had been flattened, and as the forward movement continues, the bag bottom is received in part between the aforesaid blade member 84, and a lower blade member 85, Fig. 9. (The blades 84, 85 and their support serve the purpose of gripper 13 of Fig. 1.) At about the time the bar 61 arrives at this position, or shortly thereafter, its linear motion stops; it is rocked by cam 83 in counterclockwise direction and thus the blades 84, 85 cause the forward or left-hand end of the bottom bag to disengage the stack-supporting rod 59 and move downwardly through the gap between rod 59 and the adjacent ends of flanges 58. The bar 61 then resumes its movement to the left, the bottom bag is slid along the flange members 58 and out of the gap between bar 59 and supporting members 58. The forward movement of the gripper or pusher 13 continues until the leading edge of the bag is received by the bight of the rolls 86, 87 which, as hereinafter described, complete the withdrawal of the bag B from the stack.

In brief summary, as each bag in turn becomes the lowermost bag of the stack, its forward end and its bottom, thereat folded against its under side, are deflected or separated from the stack, and the bag is moved forward with its bottom and sides in substantially the same relative positions they occupied when in the stack before aforesaid deflection or separation of the bag end and bottom. Because the bag bottom is not, in withdrawing the bag from the stack, folded backwardly against the upper side of the bag, there is avoided creasing of the other or upper side of the bag; such creasing, characteristic of prior arrangements for removing bags from a stack, is undesirable because causing the bag bottom, when freed from the restraint incident to its withdrawal from the stack, to move into position substantially at right angles to the plane of the body of the bag with consequent difficulties in its further feed or handling.

During the feeding movement of the bag by the rolls 86, 87, the carriage 60 reverses its movement to carry the bag-removing tools 84, 85 back to

their original position in readiness for removal of another bag from the stack.

The feed-roll 87 is on shaft 88 which extends through the frame member 56 and to which, exteriorly of the frame, is attached a gear 89 in mesh with the aforesaid gear 72 on shaft 71. The gear 90 on shaft 88 is in mesh with the gear 91 on the shaft of the upper feed roll 86. Preferably and as indicated, the upper feed roll is provided with two notches 92, 93 extending longitudinally thereof, the distance between the notches corresponding substantially to the width of one-half of the bag bottom, and its operation is so timed that notch 92 receives the leading end of the bag B as fed toward it by the reciprocating carriage 60; the other notch 93 therefore comes into engagement with the bag at the portion of maximum thickness of the folded bag as it is about to enter the bight of the two rolls.

As the bag emerges from between the rolls 86, 87, it is directed by the guides 94, 95, 95 to the front end of the table 96 where it is engaged by the fingers 97 which extend upwardly from the rocker arm 98 on the shaft 99 extending between the frames 56, 57. Arm 98 is connected by link 100 to lever 101 on shaft 102 from which extends the arm 103 having thereon a cam follower 104. The spring 105 connected to arm 106 on shaft 102 biases the cam follower 104 into engagement with cam 107 on shaft 71.

The angular position of the cam 107 on shaft 71 is such that substantially concurrently with feed of a bag by rolls 86, 87, the fingers 98 swing in clockwise direction to push the bag previously delivered to them between the feed roll 87 and the lower feed roll 108 driven from the shaft 88 by gears 90 and 109, and before completion of feeding of the bag by the rolls 86, 87, the fingers 97 have been returned to their receiving position, Fig. 8.

The rolls 87, 108 feed the bag, open end foremost, toward the closure strip ST and drop it on to the spaced plates 110, 111.

The bag is registered in position partly to overlie the composite closure strip ST between successive notches by the stops 112, 112 which are mounted for free vertical movement in the fixed frame member 113 of the machine, by the guide plate 114, by the fingers 115 movable to engage the side of the bag, and by finger 116 movable to engage the end of the bag.

By mechanism hereinafter described, the finger 116 pushes the bag forwardly until the open or leading end of the bag is engaged by the stop members 112 properly to determine the extent of overlap of the bag with the closure strip ST, and the fingers 115 push the bag sidewise until arrested by the stop 114 properly to register the bag between the notches in the closure strip.

The fingers 115 are secured to shaft 117 and are biased to position below the plane of the bag by the springs 118. To shaft 117 is secured the L-shaped arm 119 in the path of the cross-member 120 on the lever 121 which, as appears in Fig. 6, is adapted to be rocked by the cam 122 on shaft 71. The cam is so timed that after delivery of a bag from the rolls 87, 108, the fingers 115 swing upwardly for sidewise registry of the bag and then substantially immediately spring back to their position to permit subsequent movement of the bag by feed belts 122, as hereinafter described. The finger 116 is attached to shaft 123 from which extends an arm 124 in the path of the aforesaid cross-bar 120 on arm 121. Substantially concurrently with operation of fingers 115, the

finger 116 swings upwardly from below the plane of plates 110, 111, to push the bag forwardly to position defined by the stops 112.

After this registration of the bag with respect to the closure strip ST, the frame 48 is automatically raised by the cams 50 to press the strip ST into firm adhesive engagement with the bag. Substantially concurrently, the notching knives 10, 11 are moved toward engagement with the

strip.

By the next feeding movement of the closure strip ST, the attached bag is moved with the strip beyond the assembly station to bring the next pair of notches in the strip in position in registry with the assembly station, and while the strip is in this position, another bag is registered and attached thereto, as previously described; concurrently with the upward movement of the member 48, to press that bag into engagement with the strip at the assembly station, the knife 12 is rocked to sever the closure strip and detach therefrom the assembly comprising the bag previously attached to the strip. This assembly may, as generically indicated in Fig. 1, be carried away from the machine by the conveyor belts 15 which may run continuously or intermittently at suitable speed.

Particularly to insure proper feed when there are only a few bags in the stack, there are provided the belts 125, Fig. 18, which engage the sides of the stack preferably near the forward end substantially in line with the gap between support 59 and supports 58. Each of the belts at its upper end passes over an idler pulley 163 on shaft 126 extending between the frame members 127, 217 (Fig. 5) and at its lower end passes under a pulley 128 on a shaft 129 which extends through the frame members 127 and is provided with a worm gear 130 in mesh with a worm wheel 40 131 on shaft 132. The shaft 132 is intermittently advanced by the arm 133 loosely pivoted on shaft 132 and having its lower end disposed in the path of an abutment 134 on the reciprocating rack member 68 (Fig. 5). As the rack member moves to the left, Fig. 5, the arm 133 is rocked in clockwise direction, the pawl 135 on the arm engaging the ratchet 136 on shaft 132 to effect movement of the belts 125; upon reverse movement of the rack member 68 the spring 137 returns the arm 133 to its original position.

The belts 125 serve to pack the bags firmly against the bar 59 and insure opening of the fold F; use of belts 125 or their equivalent is particularly necessary when the bags are of stiff material because, in their absence, feeding of bags from the stack may be subject to frequent delays due to failure of fold F to open.

It has been found that when the forward end of the bag-removing tool 85 was straight, the tool would sometimes abut the edge E of the bag-bottom and would not enter the fold between the bag-bottom and the side. This difficulty was overcome by forming the tool, as shown in Fig. 13, with a cutaway or recess. For feeding bags having a bottom flap of the shape shown in Figs. 10, 11, it was also found desirable to provide a deep cutaway in the lower blade 85, for it was found that if this blade had a straight edge, difficulty in feeding was sometimes experienced because of occasional engagement of the tool with the edge of the bottom flap. These feeding difficulties were particularly troublesome when the machine was operated at high speed, for example, at from about 150 to 200 cycles or bags per minute.

Particularly because the machine is capable

of operation at high speed, it is desirable that it stop promptly upon interruption of the feeding of bags from the stack or to the assembly station; otherwise, a substantial amount of strip material is wasted. To that end, the feed rolls 86 and 108 are electrically insulated in any suitable manner from the frame of the machine except when they are in contact with the intermediate feed roll 87. The shaft of roll 86 is supported by arms 138 which are biased as by spring 139 to effect engagement of roll 86 with roll 87. When a bag is delivered to the rolls by the reciprocating carriage 60, as previously described, the feed rolls 86, 87 separate slightly to permit passage of the bag, but not, of course, to sufficient extent to permit disengagement between the gears 90 and 91. Similarly, the feed roll 108, carried by arms 140, is biased, as by spring 139, into engagement with the intermediate feed roll 87 so that during feed of a bag by rolls 108 and 87, they separate to permit passage of a bag toward the assembly station. As above described, these two feeding actions are substantially concurrent, i. e., while one bag is being fed by rolls 86, 87 toward fingers 97, another bag is being fed by the rolls 87 and 108 towards the assembly station. Under normal conditions, therefore, both of rolls 86, 108 should be out of engagement with roll 87 for a predetermined portion of the machine cycle, and for the remainder of the cycle, these rolls are in electrical contact with the roll 87.

As indicated in Fig. 17, a switch 141 or equivalent is connected in series with the intermediate roll 87, a translating device, generically represented by the solenoid 142, and a suitable source of power indicated conventionally by a battery 143. The switch 141 is controlled by a cam 144 attached to any element of the machine which makes, for the particular cam shown, one revolution per cycle of the machine, and the angular position of the cam is such that the switch 141 is open except for that portion of the cycle during which bags should be between the feed rolls 87 and 87, 108. If, while switch 141 is closed, there is no bag between either of these pairs of feed rolls, a circuit is completed through the translating device 142 either to give an alarm signal, or preferably immediately to interrupt the operation of the machine. Specifically, the translating device 142 may be an electromagnet whose armature 145 is connected to the latch 146, which holds the control lever 147 of the machine in position to effect its continuous operation. When the solenoid is energized, as above explained, the latch is released, whereupon the control lever, as by spring 148, gravity, or equivalent, at once moves to position interrupting further operation of the machine.

For the bag-feeding mechanism of Figs. 4, 5 and 6 may be substituted the generally similar mechanism of Figs. 22-25 of which it is characteristic there is omitted the lower feed roll 108 of Figs. 4 to 7, and in which a reciprocating slide 165 replaces the feed roll 108 and the oscillatory arm 97 of Figs. 4 to 7; other differences of construction are apparent from the following description but insofar as the constructions are similar, the same reference characters are used to identify corresponding parts.

Referring to Fig. 25, the bags are removed in succession from the bottom of the stack, by reciprocating mechanism identical with that previously described, and in succession are presented to the feed rolls 86, 87, which move the

bag to the left, Fig. 25, until the trailing end of the bag clears the rolls whereupon the bag falls between the guard rails 95A, 114A, in front, or to the right of, the abutment 166 which extends through the slot 167 in the feeding table. The slide 165 which carries the abutment 166 is guided by the two rods 168 which are supported below the feeding table by the brackets 169 and 170. To the slide 165 is attached the rack 171 in mesh with the gear 172 on shaft 173 which extends through the side frames 56, 57 and to one end of which, Fig. 23, is attached the gear 174 in mesh with the gear segment 175 at the end of arm 176 pivotally mounted on stud 177 extending from the side frame 56. The cam follower 178 carried by the arm 176 engages the cam 179 on the one-time shaft 11; arm 176 is biased by spring 180 to maintain engagement between cam follower 178 and cam 179. During each revolution of cam 179 the gear segment 175 oscillates to and from the position shown in Fig. 22 to effect rotation of gear 172, Fig. 25, first in one direction and then in the other to reciprocate the abutment 166 from and back toward its position, Fig. 25. During the movement of the abutment 166 to the right, Fig. 25, a bag is pushed thereby between the guide rails 95A, 114A toward the closure-applying mechanism or other destination.

To prevent the forward end of the bag from being turned upwardly or back during its movement by slide 165, there is provided the elongated arm 181 provided with a fulcrum pin or knife-edge 182 engaging a bearing block 183 near the left-hand end of the feed table, Fig. 25. The arm 181 is so biased by spring 184 that its forward end, during feed of a bag by rolls 86, 87, is above the line of discharge of a bag from the feed rolls. After a bag has cleared the rolls and before its movement by pusher 165, the end last to clear the rolls is pushed downwardly by arm 181 under the control of mechanism now described. Between its pivot 182 and its right-hand end, the arm 181 is engaged by a finger 186 suitably attached to a sleeve 187 on the cross bar 188 extending between side frames 56 and 57. From the sleeve 187 depends an arm 189 having at its lower end a cam follower 190 in continuous engagement with the periphery of a cam 191 on shaft 11. The angular position of the cam 191 is such that substantially immediately a bag has entirely passed beyond the feed rolls 86, 87, the sleeve 187 is swung in counterclockwise direction, whereupon finger 186 depresses the arm 181 to bring the right end thereof substantially below the line of discharge of a bag from the feed rolls. The leading end of the bag is prevented from turning upwardly after it has passed beyond the arm 181 by the plate 192 welded or otherwise suitably attached to the guide 114A; preferably the plate 192 is so shaped, Fig. 25, that in cooperation with the feeding table it forms a passage converging in the direction of feed of the bag. Cam 191 is so shaped that before the next bag is fed to rolls 86, 87, the spring 184 has returned the arm 181 to its original position indicated in Fig. 25.

Because of the omission of the lower feed roll 108 and supporting arm 140, a somewhat different arrangement is utilized in the mechanism of Figs. 22 to 25 to bias the roll 86 into engagement with the roll 88. As indicated in Figs. 23 and 25, each of the arms 138 is provided with extension 193 whose uppermost position, Fig. 25, is defined by a stop pin 194 threadably engaged by the ledge 196

which extends from the side members 56, 57, respectively. When a bag passes between the rolls 86, 87, the spring 195 is tensioned to bias the roll 86 to its original position, Fig. 25.

In this modification, the mechanism for registering the bag is somewhat different from that disclosed in Figs. 4 to 7; specifically, as the rack 171 approaches the right-hand limit of its travel, Fig. 25, its forward end engages the arm 198 biased against the adjustable stop 199 by spring 200. The clockwise movement of arm 198 is communicated through arm 201 and link 202 to the registering finger 115A on shaft 203. This movement of finger 115A away from the observer, Fig. 25, or toward the bottom of the sheet, as viewed in Fig. 23, insures alignment of the bag with the guide rail 114A and thus insures the bag is in proper position to receive a closure member, as hereinbefore described.

In this modification also, the belts 125 of Figs. 4 to 7 are dispensed with and in lieu thereof are utilized the two star wheels 204 or equivalent; the star wheels are mounted upon the shaft 132 which, as previously described, is intermittently moved in one direction, specifically clockwise, as viewed in Fig. 25. The star wheels are so positioned, as more clearly shown in Fig. 19, that they engage the forward ends of bags in the stack H while the bags so engaged are above the position for which the distance or spacing between the rear guard rails 159 and the forward guard rails is more or less exactly equal to the length of the collapsed bags. The plate 159, as appears in Fig. 19, is curved so that the length of the hopper near the top thereof is suitably greater than the length of the collapsed bags to facilitate dropping groups of bags into the hopper. Above the star wheels, the bags, as illustrated by Fig. 19, are not in alignment with each other, but in passing the star wheels they are all aligned because each, in turn, as it passes the star wheel is forced to the right, Fig. 19, to bring its right-hand edge against the guard bars 159. The star wheels also insure that the bottom bag of the stack is always in the position of the bottom bag of Fig. 29 and is not, because of friction, or misalignment, held above the position of the bottom bag of Fig. 29 and so incapable of being removed from the stack by the transfer mechanism 84, 85.

The star wheels 204 serve to press the stack of bags firmly against the bar 58 and so insure opening of fold F of the lowermost bag even though the bags are of stiff material; the coaction of the forward end of member 151 which bends the bags upwardly, Fig. 19, their bottom panels and the star wheels 204 which force the forward ends of the bags downwardly is very effective to open the folds F and insures removal of the bags by the feeding mechanism.

What I claim is:

1. The method which comprises arranging collapsed bags in a stack with each bag having its bottom flattened against a side of the bag and with all bag bottoms presented toward the same end of the stack, engaging the end bag of the stack within the fold defined by the flattening of the bag bottom against said side of the bag, turning the bottom of the bag in its entirety away from the stack in direction to maintain said fold substantially closed, and thereafter removing the bag bodily from the stack in direction substantially parallel to the stack and away from the open ends of the bags thereof.

2. The method which comprises arranging collapsed bags in a stack with each bag having its

bottom flattened against a side of the bag and with all bag bottoms presented toward the bottom of the stack, supporting the bottom bag of the stack at points permitting partial opening of the fold defined by flattening of the bag bottom against its side, and removing the bags in succession from said stack by turning the entire bottom of each bag when at the bottom of the stack away from the bottom of the stack and in direction to maintain said fold substantially closed, and by thereafter sliding the bag from the stack.

3. In the art of making bag and closure assemblies, the method which comprises intermittently feeding a strip of closure material along a path toward an assembly station, during the feeding movement of the strip, removing bags in succession from a stack thereof and feeding them endwise and in succession to said assembly station, and, while the strip is stationary, attaching a bag at said assembly station to said strip and severing the strip beyond said assembly station to form an assembly comprising a bag and thereto attached closure member.

4. In the art of making bag and closure assemblies, the method which comprises feeding a strip of closure material toward an assembly station, notching the strip at regular, longitudinally spaced intervals, removing bags in succession from a stack and feeding them in succession to said assembly station, at said assembly station attaching the bags in succession to said strip between successive notches, and severing the strip at each notch to form assemblies each comprising a bag and thereto attached closure member.

5. In the art of making bag and closure assemblies, the method which comprises intermittently feeding a strip of closure material toward an assembly station, at a station in advance of said assembly station notching the strip while it is at rest, during movement of the strip, removing bags in succession from a stack and feeding them to said assembly station, at said assembly station and while the strip is at rest, applying the bags in succession to said strip between notches thereof, and while the strip is stationary severing the strip at each notch in succession to form assemblies each comprising a bag and thereto attached closure member.

6. In the art of making bag and closure assemblies, the method which comprises intermittently feeding a strip of closure material toward an assembly station, at a station in advance of said assembly station notching the strip while it is at rest, during movement of the strip, removing bags in succession from a stack and feeding them to said assembly station, at said assembly station and while the strip is at rest, applying the bags in turn to said strip between notches thereof, and while the strip is stationary severing it beyond said assembly station at each notch to form assemblies each comprising a bag and thereto attached closure element.

7. In the art of making bag and closure assemblies, the method which comprises adhesive-coating a strip of closure material and feeding it toward an assembly station, feeding a narrow strip of ductile metal toward said assembly station, curling an edge of said coated strip of closure material to enclose said strip of ductile metal, notching the other edge of said strip of closure material, removing bags in succession from the bottom of a stack thereof and at said assembly station pressing them in succession into adhesive engagement with said strip of

closure material between successive notches, and at or beyond said assembly station severing said strips at the notches in succession to provide assemblies each comprising a bag and thereto attached closure element.

8. A machine for making closure members and attaching them across the open ends of bags comprising mechanism for intermittently feeding a strip of closure material, mechanism for removing bags in succession from a stack and applying them in succession to said strip while it is at rest, and mechanism for severing the strip extending between successively attached bags.

9. A machine for making closure members and attaching them to bags comprising means for feeding a strip of closure material and a narrower strip of ductile metal toward an assembly station, tool structure for turning an edge of said strip of closure material to embrace said metal strip, mechanism for notching the unturned portion of said strip, means for feeding bags in succession into adhesive engagement with the unturned portion of said strip, and means for severing the strip at each notch to detach from the strip a bag and a closure element attached thereto.

10. Mechanism for intermittently feeding a strip of closure material to an assembly station, means for registering a bag at said station in part to overlie said strip comprising bag-engaging structure movable substantially parallel to said strip and bag-engaging structure movable substantially at right angles to said strip, and mechanism timed to press the registered bag and said strip into adhesive engagement with each other while said strip is at rest.

11. A machine comprising structure for supporting a stack of bags, each with its bottom folded against a side thereof, and means for removing the bags in succession from said stack comprising a bag-engaging tool, means for rectilinearly reciprocating said tool in a path substantially parallel to the bottom of said stack to engage the end bag of the stack within the fold between said side and bottom, and means for effecting angular movement of said tool to swing the bag bottom to the opposite side of said support prior to completion of a bag-removing stroke of said tool.

12. A machine comprising means for supporting a stack of collapsed bags, a feed-roll having a notched periphery, and mechanism for removing bags in succession from said stack and feeding them, closed end foremost, toward said feed-roll comprising bag-feeding structure reciprocating in timed relation to rotation of said feed-roll to deliver the leading edge of each bag in turn to a notch in said feed-roll.

13. A machine comprising means for supporting a stack of collapsed bags, a feed-roll having notches in its periphery, the distance between notches being substantially equal to half the width of the bag bottom, and mechanism for removing bags in succession from said stack and feeding them, closed end foremost, toward said feed-roll and timed to deliver the leading edge of each bag to one of said notches, another notch subsequently engaging between the thickest and next thickest section of the bag bottom.

14. A machine comprising means for supporting a stack of collapsed bags, and means for removing bags in succession from the stack comprising a thin member for entering the fold between the bottom of the end bag of the stack and the side of the bag against which the bottom was

flattened, a second member slightly spaced from said first member to receive the bag bottom, a support for said members, and mechanism for moving said support adjacent an end of the stack.

15. A machine comprising structure for supporting a stack of collapsed bags at a lower edge thereof, a second stationary stack-supporting structure having a raised portion for engaging the bottom bag of the stack to bow it upwardly slightly and spaced from said first structure to expose the bottom of the lowest bag of the stack, and means for engaging the exposed bag bottom and withdrawing the bag from the stack through the space between said supporting structures.

16. A machine comprising a hopper for a stack of collapsed bags, means operating intermittently to remove bags in succession from an end of the stack including a member for entering the fold between the bottom and side of each bag in turn, belts for frictionally engaging opposite sides of the stack, and means for intermittently moving said belts in direction to feed the bags toward said end of the stack and insure opening of said fold for entry of said member.

17. In a machine comprising means for supporting a stack of bags, mechanism for feeding bags from the stack to an assembly station including feed rolls, a control circuit comprising a switch periodically closed at a predetermined time in the cycle of said mechanism, a translating device, in circuit with said switch and said feed-rolls, energized when said switch is closed in event said rolls are not then separated by a bag, and means controlled by said translating device upon energization thereof to effect discontinuance of the operation of said bag-feeding mechanism.

18. In a machine comprising means for supporting a stack of bags, mechanism for feeding bags from the stack to an assembly station comprising feed rolls, mechanism for feeding bag closure material to said assembly station, a control circuit comprising a switch periodically closed at a predetermined time in the cycle of said machine, a translating device, in circuit with said switch and said feed-rolls, energized when said switch is closed in event said rolls are not then separated by a bag, and means controlled by said translating device upon energization thereof to effect discontinuance of the operation of said second-feeding mechanism.

19. Mechanism comprising structure for supporting a stack of bags, feed rolls disposed adjacent an end of said stack, means for removing bags in succession from said stack and feeding them to said rolls for movement to a transfer station, linearly reciprocating structure for moving the bags in reverse direction from said transfer station, and means operating intermittently to prevent the bags during their movement in reverse direction from engaging said rolls.

20. Mechanism comprising structure for supporting a stack of bags, feed rolls disposed adjacent an end of said stack, means for removing bags in succession from said stack and feeding them to said rolls for movement to a transfer station, linearly reciprocating structure for moving the bags in reverse direction from said transfer station, and means operating intermittently to prevent the bags during their movement in reverse direction from engaging said rolls and for aligning them before termination of said movement.

21. In bag-feeding apparatus, a hopper for a

stack of bags comprising structure for engaging a lower edge of the stack, plate structure at the bottom of the hopper terminating short of said first-named structure, and a member pivotally mounted upon said plate structure adjustably to bow the bottom of the stack.

22. In bag-feeding apparatus, a hopper for a stack of collapsed bags comprising structure for engaging the lower front edge of the stack, a member at the bottom of the stack for bowing it upwardly intermediate its ends, and means operating to press the forward ends of the bags downwardly against said structure to insure opening of the fold between each bag bottom and its lower side.

23. The method of withdrawing a bag from a stack of bags having their bottoms at an end of the stack and folded against their sides, which comprises concurrently deflecting an end of the bag and its bottom away from the stack while the body of the bag remains stationary in the stack, and thereafter withdrawing the bag from the stack without substantially further unfolding its bottom from its side.

24. The method of withdrawing from a stack of bags a bag with its bottom at an end of the stack and flattened against the side of the bag, which comprises deflecting an end of the bottom bag and its bottom from the bottom of the stack, and thereafter withdrawing the bag from the stack.

25. Apparatus for removing bags from a stack thereof having their bottoms at the front of the stack and flattened against their sides, comprising means for deflecting the front end of the bag and its bottom away from the stack while the remainder of the bag remains at rest, and means for thereafter withdrawing the bag forwardly from the stack past the front end of the stack.

26. A machine comprising structure for supporting a stack of bags with their bottoms flattened against their sides, and means for removing the bags in succession from the stack comprising a tool for entering the fold between the bottom and side of a bag, and means for turning said tool, while within said fold and in engagement with the bag, about an axis substantially parallel to one end of the stack.

27. In the art of making bag and closure assemblies, the method which comprises removing bags in succession from a stack and feeding them end to end, feeding a strip of closure material in direction normal to the direction of feed of the bags to bring successive portions of the strip in position to extend across successive bags at their open ends, effecting attachment of the successive bags to aforesaid successive portions of said

strip of closure material, and severing the strip to provide assemblies each comprising a bag and a closure member extending across the open end thereof.

5 28. In the art of making bag and closure assemblies, the method which comprises removing bags from a stack thereof and feeding them end to end, intermittently feeding a strip of closure material in direction normal to the direction of feed of the bags to bring successive portions of the strip in position to extend across successive bags at their open ends, and, while the strip is at rest between successive feeding movements, attaching a bag thereto and severing the strip to form an assembly comprising a bag and a closure member extending across the open end thereof.

10 29. In the art of making bag and closure assemblies, the method which comprises sliding bags, closed end foremost, from a stack thereof and feeding them end to end, open end foremost, toward an assembly station, feeding a strip of closure material toward said assembly station by steps each substantially corresponding with the width of a bag, attaching successive portions of the strip to overlie the open ends of successive bags, and severing the strip to form assemblies each comprising a bag and a closure member extending across the open end thereof.

15 30. A machine for making bag and closure assemblies comprising intermittently operated mechanism for feeding a strip of closure material step-by-step toward an assembly station, cyclically operated mechanism operative during each cycle to feed a bag open end foremost to said assembly station, reciprocating means at said assembly station for effecting adhesive attachment of the leading portion of the strip across the open end of each successive bag, and means operative between successive cycles of said bag-feeding mechanism to sever from the strip the leading portion thereof attached to the bag.

20 31. A machine comprising spaced structures for supporting a stack of collapsed bags each with its bottom folded against a side thereof and with the bottom of the end bag of the stack exposed between said structures, means for removing bags in succession from the stack including a member for entering the fold between the exposed bottom and side of the end bag of the stack, and a belt for frictionally engaging a side of the stack movable to feed the bags toward said supporting structures to ensure opening of said fold of each bag as its bottom is exposed between said structures for entry of said member.

WILLIAM E. HIGGINBOTTOM.
